UNITED STATES PATENT OFFICE.

WILLIAM W. NUGENT, OF CHICAGO, ILLINOIS.

CONTINUOUS OILING AND FILTRATION APPARATUS.

1,207,067.

Specification of Letters Patent.

Patented Dec. 5, 1916.

Application filed November 28, 1913. Serial No. 803,431.

To all whom it may concern:

Be it known that I, WILLIAM W. NUGENT, a citizen of the United States, residing at Chicago, in the county of Cook and State of Illinois, have invented certain new and useful Improvements in Continuous Oiling and Filtration Apparatus, of which the following is a specification.

This invention relates to an apparatus in which both the oil pump and the filter will be continuous in operation whenever the apparatus to which it is applied is also in operation, with means insuring that the pressure of oil circulated will be a certain pressure determined amount and will not exceed this pressure.

The principal object of the invention is to provide new and improved apparatus for circulating oil, maintaining it at constant and uniform pressure and for providing pumping and filtering devices which will operate continuously when the engine is operated.

For the attainment of these ends and the accomplishment of other new and useful objects as will appear, the invention consists in the features of novelty in the construction, combination and arrangement of the several parts generally shown in the accompanying drawing and described in the specification, but more particularly pointed out in the appended claims.

In the drawings Figure 1 is a perspective view of a complete apparatus constructed in accordance with the principles of my invention and applied to an engine of the reciprocating type; and Fig. 2 is a detail of the pump and relief valve connections.

In the drawings, the numeral 5 designates generally an engine of the reciprocating type having eccentrics 6 and other reciprocating and rotary parts, to which the present invention is applied. The bearings of an engine of this type are usually lubricated by a continuous flow of clean oil which is supplied through a system of oil circulating mains designated generally by the reference numeral 7. A number of drip and discharge valves are connected to the circulation mains 7 in the well known manner, as illustrated in the drawings, and at the highest point of the apparatus is a gravity oil receptacle 8 to which oil is discharged through a manually controlled valve 9.

Used oil is collected and discharged into

a continuous filter 10 by means of the oil return mains 11. This filter 10 comprises any suitable type of continuous filter which is provided with a continuous water overflow 10^a and with a clean oil receptacle 12. 60 Connected from the top of the gravity receptacle 8 to the clean oil receptacle 12 is an overflow pipe 13. Also connected with the clean oil receptacle 12 is a pump suction pipe 14. A pump 15 of the single acting 65 reciprocating type is connected at one end to the engine base and at the other end to a reciprocating part of the engine, as for example, to one of the eccentrics 6 and has a single suction and discharge pipe 16. Interposed between the suction pipe 14 and the pump suction and discharge pipe 16, is a check valve 17, and interposed between the circulation mains 7 and the pump suction 70 and discharge pipe 16 is a check valve 18. 75 These check valves are of any well known type and cause the fluid to be drawn from the suction pipe 14 through the check valve 17 and to be discharged through the check valve 18 into the oil circulation mains. 80

A relief valve 19 is connected to the circulation mains 7, and extending from the relief valve is a discharge pipe 20 which is connected around the check valves 18 and 17 and with the suction pipe 14 so that if the 85 pressure of the fluid pumped is too great the oil will flow through the relief valve 19 through the pipe 20 to the pump suction pipe 14.

In operation the pressure of oil in the oil circulation mains is controlled by means of the manually operable valve 9, which permits more or less of the oil pumped to pass to the reservoir 8. If a large amount is allowed to pass to the reservoir 8 the pressure 90 in the oil circulation mains will be somewhat reduced, and if the opening of the valve 9 is restricted the pressure of the oil in the circulation mains may be much greater. The relief valve 19 limits the pressure 95 of the oil in the circulation mains, and when the pressure becomes too great the oil will simply be shunted through the bypass 20. 100

What I claim is:

1. In an oil filtration and circulation apparatus, the combination with oil circulation mains, oil drip return mains, a continuous filter in connection with the oil drip return mains, a gravity feed reservoir in connection 110

with and above the circulation mains, an overflow pipe connected from the top of the reservoir to the bottom of the filter, a pump connected with the filter and with the oil circulation mains, check valves to cause the pump to discharge oil from the filter into the circulation mains, and a relief valve and by-pass connected around the check valves to limit the pressure of oil in the circulation mains.

2. In an engine oil filtration and circulation system, the combination with oil circulation mains, of drip return mains, a continuous filter in connection with the drip return mains, a reservoir in connection with the oil circulation mains, an overflow pipe in the reservoir connected to the bottom of the filter, a reciprocating pump in connection with the moving part of the engine, a pipe connection between the filter and the oil circulation mains, a single tubular connection from the pump to the said pipe, a check valve in the pipe on both sides of the tubular connection whereby the reciprocating action of the pump will cause the pump to draw oil from the filter and to discharge it into the circulation mains, a relief valve and by-pass connected around the check valves, the relief valve being on the side adjacent the oil circulation mains, and a manually operable valve controlling the passage of oil to said reservoir whereby the pressure in the circulation system can be varied at will.

3. In an apparatus of the class described, the combination with a suction main, of a circulation main, a single pump suction and discharge pipe, check valves connecting the pump suction and discharge pipe with each of said mains, and both permitting the motion of the fluid pumped in the same direction, an overflow tank connected with said circulation main, a manually operable valve controlling the passage of fluid into said overflow tank, and a relief valve and overflow pipe connected from the circulation main forming a shunt around the check valves.

4. In an apparatus of the class described, the combination with a single acting pump, of a double check valve inlet and discharge connection therefor, a fluid circulation main in connection with the pump, a gravity feed supply reservoir also in connection with the circulation main, a manually operable valve to control the discharge of fluid from the main into the reservoir and thereby to control the pressure of fluid in the circulation main, and an overflow discharge connection for the reservoir.

5. In an engine oil circulation and filtration apparatus, the combination with oil circulation mains, of a gravity reservoir at the highest point of the system connected to the mains, a manually operable valve to control

the oil flowing into the reservoir, oil drip return pipes, a continuous filter in connection therewith having a clean oil receptacle, an overflow connection from the gravity reservoir to the clean oil reservoir, a suction pipe in connection with the clean oil receptacle, a single acting pump connected to the engine eccentric, check valves connecting the pump with the oil suction pipe and with the oil circulation mains, and a relief valve connected to the oil circulation mains with an overflow connection to the suction pipe whereby the pressure in the circulation mains will not exceed a predetermined amount.

6. In an engine oil circulation and filtration apparatus, the combination with oil circulation pipes, oil return pipes, a filter into which the return pipes discharge, a reservoir connected to the circulation pipes, a valve to control the admission of fluid thereto, an overflow pipe with an inlet opening at the top of the reservoir leading to the filter, a pump operated directly by the engine to draw oil from the filter and discharge it into the circulation pipes, a relief valve in connection with the circulation pipes and a pipe connecting the relief valve with the pump connection to the filter to form a shunt connection for limiting the pressure in the circulation pipes.

7. In a lubrication distribution system, the combination with a pump, of a plurality of lubricant feeding devices at the points of distribution, a lubricant circulating main between said pump and said feeding devices, said circulating main having a vent branching therefrom, safety mechanism for limiting the maximum pressure in said circulating main, and a valve for throttling the flow of lubricant from said main through said vent to control the pressure in the circulating main below said maximum pressure.

8. In a lubricating system, the combination with oil distribution mains, of means for positively directing the oil through said mains, a gravity feed reservoir connected to said mains from which they may be fed, and means controlling the flow of oil to said reservoir and thereby controlling the pressure in the mains.

9. In a lubricating system, the combination with mains, of means for directing the liquid into said mains, a gravity feed reservoir connected to said mains, a valve for controlling the flow of liquid from said mains into said reservoir to regulate the fluid pressure in the mains, and an overflow pipe associated with said reservoir.

10. In a lubricating system, the combination with mains, of a pump for forcing liquid through said mains, a by-pass for said pump and connected to said mains, a tank connected to said mains, a valve for con-

trolling the flow of liquid from said mains into said tank, and a relief valve in said by-pass to effect local circulation in the latter when the pressure in said mains reaches 5 a predetermined amount.

11. In combination; an engine, a pump connected to and operated by the engine, oil circulating pipes connected to the pump and adapted to deliver oil to bearings of the engine, an oil overflow tank connected with the circulating pipes, and a manually operable valve in said pipes adapted to control the supply of oil from said pipes to the overflow tank to control the pressure of oil in 15 said pipe.

12. In combination, an engine having a crank shaft and bearings therein, a pump connected with the crank shaft and adapted to be operated by and in fixed relation with 20 said crank shaft, circulating mains connected to said pump and adapted to deliver oil to said bearings, an overflow pipe connected with the circulating mains, and a valve in said overflow pipe operable independently 25 of pressure in said pipe adapted to control the flow of oil from the circulating mains to control the pressure of oil in said mains.

13. A circulating main, a pump for pumping oil into said circulating main, safety 30 mechanism for preventing the pressure in said circulating main from exceeding a predetermined maximum, and automatic means for regulating the pressure in said circulating main below said predetermined maxi-

35 mum.

14. A fluid circulating main, a pump for pumping oil into said main, a bypass safety device connected to said pump and said circulating main for preventing the pressure in 40 the latter from exceeding a predetermined maximum, and automatic means for regulating pressure in said circulating main below said maximum.

15. Oil mains having a vent branching 45 therefrom, a pump connected with the mains for directing oil into the latter, a safety device for preventing the pressure in said mains from exceeding a predetermined maximum, and means connected with said 50 vent for varying the pressure of oil in said mains under said maximum pressure.

16. Oil distribution mains, means for positively directing the oil to said mains, automatic means for preventing the pressure 55 in said mains from exceeding a predetermined maximum, and means branched upwardly from a vent in said oil mains for regulating the pressure in said mains below said predetermined maximum.

60 17. Oil distributing mains, means for directing liquid into said mains, automatic safety mechanism for limiting the maximum pressure in said mains, and means comprising a bypass for regulating the pressure in 65 said mains below such limit.

18. Oil distribution mains, a pump for forcing liquid into said mains, a bypass around said pump a relief valve in said bypass to effect local circulation in the latter when the pressure in said mains reaches a 70 predetermined amount, an overflow tank connected to said mains and to the source of supply, and a valve for controlling the flow of liquid from said mains into said tank to regulate the pressure in said mains 75 below the limit permitted by said relief valve.

19. An engine, a pump operated by a moving part of said engine, oil distribution mains between said pump and the bearings 80 of said engine, a safety device for limiting the maximum pressure in said mains, and a manually adjustable device for regulating the pressure in said mains below the maximum pressure by shunting varying amounts 85 of oil from said mains.

20. An engine having a shaft, a pump, means connected to said shaft for operating said pump, oil distribution mains for directing oil to the bearings of said engine, a bypass around said pump, a relief valve in said bypass for limiting the pressure in said mains, a gravity overflow tank in communication with said mains, and means for controlling the flow of oil into said gravity tank 95 to effect the regulation of pressure in said mains below the maximum pressure permitted therein by said bypass and relief valve.

21. An automatic lubricating system comprising distributing mains, a pump, a source of supply, automatic mechanism for limiting the pressure in said mains, automatic means adapted for manual adjustment for regulating the pressure in said mains below the 105 maximum pressure, oil return mains, and a filter between the oil return mains and the source of supply.

22. An engine, distributing mains extending to the bearings of said engine, a source 110 of supply, a pump operated by said engine for directing the lubricant from said source of supply into said distributing mains, means connected to said pump for limiting the pressure of lubricant in said mains, a 115 gravity tank above the source of supply, an overflow pipe connected between said tank and the source of supply, a valve between said mains and said tank for controlling the return of flow from said mains to said tank, 120 mains for returning the lubricant toward the source of supply, and a filter between said return mains and said source of supply.

23. A lubricant distributing main, a pump, a source of lubricant supply connected to 125 said pump, means for limiting maximum pressure in said main, mechanism for returning the lubricant to the source of supply, a vent branching from said main, apparatus connected to said vent for regulating the 130

pressure in said main below a predetermined maximum, and a connection between said apparatus and the source of supply.

24. An engine, a pump connected to said engine to be operated thereby, a source of lubricant supply connected to said pump, an oil distribution main having points of distribution therein, automatic mechanism for limiting the pressure in said main, an overflow tank located above the points of distribution of said main, and means for controlling the flow of oil into said tank to regulate the pressure in said main below said maximum pressure.

15 25. An oil distributing main, a source of oil supply, a pump for forcing oil from said source of supply into said main, an overflow receptacle connected to said source of supply, and a valve for controlling the flow 20 of oil from said distributing main to said receptacle to regulate the pressure in said main.

26. An engine, a pump operated thereby, distributing mains extending to the bearings 25 of said engine, a source of lubricant supply, return pipes for directing used lubricant back to the source of supply, a receptacle communicating with said distributing mains, a valve for controlling the flow of lubricant 30 from said distributing mains to said receptacle, and an overflow pipe connected to the source of supply and having one end extending into said receptacle with its open end located above points of distribution.

35 27. An engine having a shaft, an eccentric mounted on said shaft, a pump, operating means between said pump and said ec-

centric, a bypass around said pump, a relief valve in said bypass, a source of oil supply, distributing mains extending to the bearings 40 of said engine, return pipes for directing used oil back toward the source of supply, a filter between said return pipes and said source of supply, a receptacle in communication with said oil distributing mains, a 45 valve for controlling the flow of oil from said distributing mains into said receptacle, and a pipe connected between said receptacle and said source of supply.

28. An automatic lubricating system for 50 engines, a pump, connections for operating said pump by a shaft of said engine, oil distributing mains extending from said pump to the bearings of said engine, a device for limiting the pressure in said distributing 55 mains, an oil supply tank connected to said pump, return pipes for directing used oil toward the source of supply, a filter between the return pipes and said source of supply, an oil receptacle connected above the 60 bearings of the engine and in communication with said distribution mains, a valve for controlling the return flow of the oil from said distributing mains to said receptacle, and an overflow pipe connected between said receptacle and the source of oil supply.

In testimony whereof I have signed my name to this specification, in the presence of two subscribing witnesses, on this 24th day of November, A. D. 1913.

WILLIAM W. NUGENT.
